UNITED STATES PATENT OFFICE.

MAX BLUM, OF BLOOMINGTON, ILLINOIS, ASSIGNOR TO DE REMER-BLATCHFORD COMPANY, OF CHICAGO, ILLINOIS, A CORPORATION OF ILLINOIS.

OIL-FILTERING ATTACHMENT FOR FURNACES.

1,332,377.

Specification of Letters Patent.

Patented Mar. 2, 1920.

Application filed March 15, 1919. Serial No. 282,937.

To all whom it may concern:

Be it known that I, MAX BLUM, a citizen of the United States, residing at Bloomington, in the county of McLean and State of Illinois, have invented certain new and useful Improvements in Oil-Filtering Attachments for Furnaces, of which the following is a specification.

My invention relates to oil burning furnaces, and the principal object of the invention is to provide means associated with the oil supply pipe of a furnace of this type for filtering and at the same time heating the oil before it reaches the burner. The heating of the oil increases its fluidity and makes possible a more efficient filtering thereof, since finer mesh screens may be employed than when the oil is cold. The increased fluidity facilitates vaporization at the burner, and tends to insure complete combustion.

The invention consists of the novel and improved constructions, arrangements and devices to be hereinafter described and claimed, for carrying out the above stated objects as will appear from the following description.

The invention is illustrated in certain preferred embodiments in the accompanying drawings, wherein:

Figure 1 shows a side elevational view of a device embodying my invention connected to a furnace;

Fig. 2 is a plan view of the heating device and furnace, shown in Fig. 1;

Fig. 3 is a front elevational view of the heating device and furnace shown in Fig. 1, and showing the heating device connected to the burner of the furnace; and

Fig. 4 is a sectional view of the heating and filtering device, taken on the line 4-4 of Fig. 2.

Like characters of reference indicate like parts in the several figures of the drawings.

The heating and filtering device comprises a casing 10 which is connected to a source of oil supply (not shown) by means of a pipe 11, provided with a valve 12 to cut off the supply of oil when desired. It is also connected to the burner 13 under the combustion chamber 14 of the furnace 15 by means of a pipe 16, provided with the valve 17 to control the flow of fuel therethrough. The burner 13, combustion chamber 14 and furnace 15 form no part of my invention,

and will not, therefore, be described in detail.

The casing 10 of the filtering and heating device is preferably formed of a single casting provided in the upper part with the 60 cylindrical bore 18 and in the lower part with the enlarged cylindrical bore 19. Between the bores 18 and 19 is the intermediate bore 20 which is somewhat smaller in diameter than the bore 19 and somewhat larger 65 in diameter than the bore 18, thus, as will be clearly seen from Fig. 4, providing the annular shoulders 21 and 22. The lower end of the heating and filtering device is internally screw-threaded and is closed by 70 means of a screw plug 23 which is preferably dish shaped and adapted to receive any sediment deposited therein from the oil. The heating device may be provided with a plurality of wire screens to strain the oil, 75 preferably the screen 24 of fine mesh and the screen 25 of coarser mesh. The screen 24 is approximately the same diameter as the central bore 20 and fits snugly against the annular shoulder 21. The screen 25 is approximately the same diameter as the lower bore or chamber 19 and fits snugly against 80 the annular shoulder 22. The screens 24 and 25 are held against the respective shoulders 21 and 22 by means of the rod 26 which 85 is threaded through the cap or plug 23. The rod 26 passes through the center of the screens 24 and 25 and is provided with a plurality of nuts 27. Preferably the nuts are adjusted on the rod 26 so that the screens 90 will be flexed slightly against the shoulders 21 and 22 to insure a close fit. The inlet pipe 11 is threaded into the lower chamber 19 and the outlet pipe 16 is threaded into the upper chamber 18. The upper chamber 95 18 may be provided with an outlet 28 in addition to the one for the pipe 16, thereby making it possible to connect the filtering device so as to supply fuel or gas to two burners, or so that it can be used on either 100 side of the furnace. The outlet 28 not in use is closed by means of a threaded plug 29. The lower chamber 19 is provided with a blow-off cock 30 so that any water or vapor that may accumulate in the lower 105 chamber 19 may be drawn off as often as required.

Heat is preferably supplied to the casing 10 by means of an overhanging hot air pipe 31 which has communication with the work- 110

ing chamber of the furnace 15. The lower end of the pipe 31 is open and terminates slightly above the top wall of the upper chamber 18 of the filtering device 10, so that 5 blasts of hot air may be blown directly from the working chamber of the furnace on to the top of the filtering device. The volume of hot air may be regulated by means of the gate or valve 32 in the pipe 31.

10 The operation of the device is very simple. The fuel oil is fed to the filtering and heating device 10 under pressure. The gate 32 is opened and a steady flow of hot air plays on the heating and filtering device 10, which 15 thoroughly heats the walls of the entire device. The heat is transmitted to the incoming stream of oil in the chamber 19 which acts rapidly to thin the oil so it will readily pass through the screens 25 and 24, even if 20 they are of very fine mesh. All foreign matter carried in the oil is freely given up and collects in the dish-shaped plug 23. Whatever water there is in the oil will be readily separated and will collect in the chamber 19 25 and may be drawn off by means of the cock 30. The heating of the oil as described facilitates its vaporization at the burner.

While I have described my invention in a certain preferred embodiment, it will be understood that modifications might be made without departure from the principles of the invention. Therefore I do not wish to be understood as limiting the invention to the precise arrangements, constructions and devices 35 shown and described, except so far as certain of the claims herein are specifically so limited.

I claim:

1. The combination with the oil supply 40 pipe of an oil burning furnace, of a filter device arranged in said supply pipe comprising a hollow body closed at the top and open at the bottom having upper and lower chambers, the oil supply pipe leading to said lower 45 chamber and leading from the top of said upper chamber, an annular shoulder formed on the inside walls of said body between said chambers, a screen, a screw plug adapted to close said body at the bottom, a rod supported on said plug and adapted to hold said screen against said shoulder, a pipe leading 50 from the combustion chamber of the furnace

for applying hot gas to said filtering device to increase the fluidity of the oil during the filtering operation.

2. The combination with the oil supply pipe of an oil burning furnace, of a filtering device arranged in said supply pipe comprising a hollow body closed at the top and open at the bottom having upper and lower chambers, the oil supply pipe leading to said lower chamber and from said upper chamber, annular shoulders formed on the inside walls of said body between said chambers, a screen of coarse mesh, a screen of fine mesh disposed over the other screen, a screw plug adapted to close said body at the bottom, a rod supported by said plug and adapted to hold said screens against said shoulders, and a pipe leading from the combustion chamber 60 of the furnace for applying hot gas to the filtering device.

3. The combination with the oil supply pipe of an oil burning furnace, of a filtering device arranged in said supply pipe comprising a hollow body closed at the top and open at the bottom having upper and lower chambers, the oil supply pipe leading to said lower chamber and from said upper chamber, annular shoulders formed on the inside walls 65 of said body between said chambers, a screen of coarse mesh, a screen of fine mesh disposed over the other screen, means to hold said screens against said shoulders, a screw plug adapted to close said body at the bottom and a pipe leading from the combustion chamber 70 of the furnace for applying hot gas to the filtering device.

4. The combination with the oil supply pipe of an oil burning furnace, of a filtering device arranged in said supply pipe comprising a hollow body closed at the top and open at the bottom having upper and lower chambers, the oil supply pipe leading to said lower chamber and from said upper chamber, annular shoulders formed on the inside walls 80 of said body between said chambers, a plurality of screens and means to hold them against said shoulders, a dish-shaped screw plug adapted to close said body at the bottom, and a pipe leading from the furnace and adapted to apply hot gas to the filtering device.

MAX BLUM.
